DRINK MIXER

W Arthur Ernst, Racine, Wis.

Application August 11, 1954, Serial No. 31,817

Term of patent 14 years

(Cl. D44—1)

Fig. 1

Fig. 2

Fig. 3

Fig. 4

Fig. 1 is a perspective view of a drink mixer showing my new design.

Fig. 2 is a rear elevational view thereof.

Fig. 3 is a cross sectional view taken along the line 3—3 of Fig. 2.

Fig. 4 is a top plan view of that shown in Fig. 1.

I claim:

The ornamental design for a drink mixer, as shown.
